UNITED STATES PATENT OFFICE.

HARRY P. BROWN, OF BOSTON, MASSACHUSETTS, ASSIGNOR OF ONE-HALF TO WILLIAM E. POWERS, OF BOSTON, MASSACHUSETTS.

GAITER.

Application filed November 1, 1922. Serial No. 598,243.

To all whom it may concern:

Be it known that I, HARRY P. BROWN, a citizen of the United States, residing at Boston, in the county of Suffolk and State 5 of Massachusetts, have invented new and useful Improvements in Gaiters, of which the following is a specification.

This invention is embodied in a gaiter, adapted to cover and conform closely to the 10 instep portion of the wearer's shoe, and to extend above the instep, and be contracted on and conformed to the wearer's ankle, the gaiter being a tube of waterproof material which is closed and impervious to water between its upper and lower ends, and is 15 adapted to be contracted, either upon the ankle within a trousers leg, or upon a trousers leg contracted upon the ankle by the gaiter.

20 Of the accompanying drawings forming a part of this specification,—

Figure 1 is a side view of a gaiter embodying the invention.

25 Figure 2 is a section on line 2—2 of Figure 1.

Figure 3 is a section on line 3—3 of Figure 1.

Figure 4 is a section on line 4—4 of Figure 1.

30 Figure 5 is a section on line 5—5 of Figure 1.

The same reference characters indicate the same parts in all of the figures.

35 My improved gaiter is a continuous tube of waterproof construction, and preferably composed of a combination of textile fabric and rubber, such as is employed in the manufacture of so-called arctic overshoes. The lower end 12 of the tube is enlarged, and 40 formed to embrace and fit snugly on the portion of the wearer's shoe which includes the instep. Said lower end is non-adjustable, or in other words, is not adapted to be contracted like the major portion hereinafter described.

45 The tube is shaped above the lower end 12 to conform to the portion of the shoe upper which surrounds the foot-receiving opening of the upper. The major portion of 50 the tube is rendered adjustable by means of bellows folds, so that said portion may be contracted about the wearer's ankle and above the latter, the tube being preferably of sufficient length from the instep portion considerably above the ankle. The said

major portion includes a front member 13, a back member 14, the forward edges of which overlap parts of the front member, and intermediate members 15, between parts of the members 13 and 14, said members being integrally connected, so that they form an adjustable tube, which is impervious to water.

As indicated by Figures 1 and 5, the intermediate portions 15 taper at their lower ends to a point at 15^a, where they join the lower end 12, and increase gradually in width from said point upward.

The described construction permits the contraction of the major portion of the 70 gaiter, about a portion of the shoe upper, and about the ankle of the wearer, adjustable fasteners being employed adapted to maintain any desired contraction, so that the said major portion may be worn within 75 a trousers leg, and closely embrace the ankle, or may be worn outside the trousers leg, and hold the latter contracted on the ankle.

75 Fasteners such as are employed on arctic overshoes are suitable for this purpose. Portions of a set of these fasteners are shown somewhat conventionally, by Figure 1, each fastener including a curved lever tongue 17, and a plate 18, having a plurality of slots, either of which may receive the tongue.

The fastener elements may be secured in any suitable manner to the gaiter at the junction of the back member 14, with the intermediate members 15.

80 The gaiter is provided, as usual, with holding-down means, attached to its lower edge, and extending across the under side of the shank portion of the shoe bottom. Said means may include strap portions 19 and 20, one portion having a buckle 21, engaging 85 the other, as shown by Figure 4.

85 The gaiter is applied by drawing it to place over the toe of the shoe, the non-adjustable lower end 12 being of sufficient size, and the adjustable major portion sufficiently 100 expandable, to permit this operation. When the lower end 12 is properly seated, the major portion is contracted and secured as described.

105 The lower end portion of the gaiter is so fitted to the portion of the shoe embraced thereby, that it may be overlapped and covered by a portion of the upper of an ordinary waterproof overshoe, known as a rubber.

2

I claim:

A gaiter composed of a continuous tube, having an enlarged non-adjustable lower end, formed to embrace and fit the instep portion of the wearer's shoe, and an adjustable major portion, having bellows folds extending from said non-adjustable end to the upper end of the gaiter, whereby said

major portion is adapted to be contracted, fastening devices being provided whereby 10 the major portion may be confined when contracted.

In testimony whereof I have affixed my signature.

HARRY P. BROWN.
